GUIDE FOR CUTTING TORCHES

Erastus E. Harris, Wilmington, Del.

Application April 11, 1947, Serial No. 740,938

2 Claims. (Cl. 266—23)

1

This invention relates to cutting torches, and more particularly to a guide for permitting straight, circular, even and efficient cutting by an acetylene torch.

As is well known, it is difficult and arduous to hold an acetylene torch in such a way as to obtain a uniform cut, especially when the work is thick, long or tough.

It is a principal object of the present invention to provide a mechanical guide, adapted to ride on the work and so designed as to hold the torch in proper position for the cutting operation, whether straight or curved.

The accompanying drawings illustrate a preferred embodiment of the invention, it being understood that modifications may be made therein without departing from the scope of the invention as claimed.

In the drawings:

Figure 1 is a front elevation of the cutting guide constructed in accordance with the principles of the invention.

Figure 2 is a top plan thereof, a portion being broken away to show the construction.

Figure 3 is a vertical longitudinal section of the device, taken from the side opposite that shown in Figure 1.

Figures 4 and 5 are elevation and front views, respectively, of a trailing wheel for insuring a straight cut.

Figure 6 is a vertical section through a fork for supporting the torch.

The guide comprises a horizontal spider 10, supported on four carriage wheels, 11, 12, 13 and 14, which are adapted to ride on the surface of the metal 15 that is to be cut. The spider 10 carries a handle 16 and the two conduits 17 and 18 that conduct the gases to the cutting tip 19. The spider 10 further carries a leading guide wheel 21 adapted to follow a line or other indicia on the surface of the work 15, and a trailing guide wheel 22 adapted to ride in the trench cut out by the torch, as will be more fully described hereinafter.

The front carriage wheels 11 and 13 are mounted for rotation on a horizontal cross-bracket 24 underneath the spider 10, by means of a shaft fixed to the bracket 24, or extending through the bracket 24, or otherwise. The rear wheels 12 and 14 are similarly mounted on a bracket 25. If desired, the wheels 11 and 12 may be connected by a connecting rod 26 to promote uniform turning and the wheels 13 and 14 may be similarly connected by a connecting rod 27.

The cross-bracket 24 is adjustably secured to the spider 10 by means of two bolts 29 tapped

2

into the bracket 24 and adjustable by means of wing-nuts 30 on the upper surface of the spider 10. A lock-nut 31 underneath the spider 10 will hold the bracket 24 in adjusted position. By this means the spider 10 may be raised or lowered with respect to the work 15, and maintained in desired position. The rear bracket 25 is similarly fastened to the rear of the spider 10.

The leading guide wheel 21 is supported by an angular bolt 33 that passes through the front bracket 24 and the spider 10, and is adjustably secured to the spider 10 by an upper nut 34 and a lower nut 35. Thus, it will be possible to elevate the guide wheel 21 to be clear of the work 15, if that is desired, or to ride thereon.

The rear guide wheel 22 has a central shoulder 36 that is adapted to ride in the cut made in the metal 15. The wheel 22 is supported on a horizontal pin 37 mounted in a bifurcated holder 38 removably secured to the rear bracket 25 or integral therewith. If desired, this holder 38 may be vertically adjustable with respect to the bracket 25 in order to permit changes in the depth of the shoulder 36 in the cut.

The spider 10 has a central aperture through which the tip 19 of the torch may be passed, and an annular rest 40 on top of the spider 10 will hold the tip 19 in place. The lower conduit 17 of the torch is supported by a fork 41, fixed to the top of a threaded member 42, and the latter passes through an aperture in the spider 10 and is adjustable vertically with respect thereto by means of a nut 43.

The conduits 17 and 18 are elastically clamped in position by three spring clamps 44 that are adapted to grip the head of the torch adjacent the tip 19. These clamps 44 pass through the spider 10 and may be adjusted thereto by the aid of nuts 45. A fourth spring clamp 46 is adapted to grip the torch farther back, and has a hook portion 47 to permit ready insertion and removal of the torch. This clamp 46 is similarly adjustable with respect to the spider. If desired, further clamps may be provided.

The handle 16 has four spring members 50 by which it may be mounted on the spider 10, the lower ends of the spring members 50 being adapted to be secured by the wing-nuts 30 on the bolts 29. The handle 16 is so designed that it and the spring members 50 can be removed and replaced on the spider 10 in reversed position, thereby providing a choice of two grips.

The operation of the device is obvious. Once it is adjusted for depth of cut, it can be easily moved along continuously, in a straight or curved line,

as desired, without varying the uniformity of cut.

If it is desired to cut circles, the carriage wheels 11, 12, 13 and 14 are removed. The leading guide wheel 21 and the trailing guide wheel 22 are likewise removed. The two front legs and one rear leg 29 are screwed up all the way, and the bottom of the remaining rear leg 29 is placed in a punch hole in the center of the circle to be cut. A front leg may be used instead of the rear leg, depending on the diameter of the circle. Alternatively all the carriage wheels may be removed and only the guide wheels utilized.

The spider 10 is cut away at 51 and 52 to permit view of the cutting, and the ends 53 and 54 may be fashioned in the shape of wrenches. Changes in the shape may be made to afford the greatest utility.

This device may be modified to accommodate electrical apparatus and similar apparatus.

What is claimed is:

1. A guide for a cutting torch comprising a horizontally elongated plate, forward and rearward wheel means longitudinally spaced along said body and each comprising a pair of laterally spaced vertically adjustable elements, a cross member beneath said plate supported by and between said vertically adjustable elements, laterally spaced work surface engaging wheels mounted on said cross member for supporting said plate for movement over the surface of the work, said vertical elements being adjustable to determine the angularity and spacing of said cross member and wheels with respect to said plate and thereby the angularity and spacing of said plate with respect to the surface of the work, a cutting torch tip fixed on said plate between said forward and rearward wheel means and directed toward the surface of the work in a manner providing a change in the angularity and spacing of said torch tip with respect to the work surface whenever the angularity and spacing of said plate with respect to the work surface is changed, a forward guide roller between the wheels of said forward wheel means for rolling upon a guide line provided on the surface of the work, means for vertically adjusting said forward guide roller to maintain contact of said forward guide roller with the work surface whenever the spacing and angularity of said plate with respect to the work surface is changed, and longitudinal handle means rising from said plate and enabling manually moving said torch over the work surface with said forward guide roller following the guide line provided on the work surface whereby said torch tip will form a cut in the surface of the work conforming to the guide line, and a trailing guide roller between the wheels of said rearward wheel means, said trailing guide roller being arranged to ride in the cut in the work surface formed by said torch tip as the torch is moved forwardly over the work surface in a manner to aid accurate manual movement of said torch over the work surface with said forward guide roller following the guide line on the work surface.

2. A guide for a cutting torch comprising a horizontally elongated plate, forward and rearward wheel means longitudinally spaced along said body and each comprising a pair of laterally

spaced vertically adjustable elements, a cross member beneath said plate supported by and between said vertically adjustable elements, laterally spaced work surface engaging wheels mounted on said cross member for supporting said plate for movement over the surface of the work, said vertical elements being adjustable to determine the angularity and spacing of said cross member and wheels with respect to said plate and thereby the angularity and spacing of said plate with respect to the surface of the work, a cutting torch tip fixed on said plate between said forward and rearward wheel means and directed toward the surface of the work in a manner providing a change in the angularity and spacing of said torch tip with respect to the work surface whenever the angularity and spacing of said plate with respect to the work surface is changed, a forward guide roller between the wheels of said forward wheel means for rolling upon a guide line provided on the surface of the work, means for vertically adjusting said forward guide roller to maintain contact of said forward guide roller with the work surface whenever the spacing and angularity of said plate with respect to the work surface is changed, and longitudinal handle means rising from said plate and enabling manually moving said torch over the work surface with said forward guide roller following the guide line provided on the work surface whereby said torch tip will form a cut in the surface of the work conforming to the guide line, and a trailing guide roller between the wheels of said rearward wheel means, said trailing guide roller being arranged to ride in the cut in the work surface formed by said torch tip as the torch is moved forwardly over the work surface in a manner to aid accurate manual movement of said torch over the work surface with said forward guide roller following the guide line on the work surface, said trailing guide roller being vertically adjustable to provide desired contact of said trailing guide roller with the cut in the work surface in conformance with the angularity and spacing of said plate with respect to the work surface.
